UNITED STATES PATENT OFFICE.

THOMAS R. HARTELL AND JOHN LETCHWORTH, OF PHILADELPHIA, PA.

DESIGN FOR A MEDAL.

Specification forming part of Design No. 7,500, dated June 23, 1874; application filed April 29, 1874.
[Term of Patent 3½ years.]

To all whom it may concern:

Be it known that we, THOMAS R. HARTELL and JOHN LETCHWORTH, of Philadelphia, in the county of Philadelphia and State of Pennsylvania, have invented and produced a certain new and original Design for a Medal; and we do hereby declare the following to be a full, clear, and exact description of the same, reference being had to the accompanying facsimile, which forms part of this specification, in which—

Figure 1 represents one or the obverse side of the medal, and Fig. 2 represents the other or reverse side of the same.

Our design for a medal consists of, first, a representation, on one side of said medal, of the exterior of the buildings of the Centennial Exposition, to be held in the city of Philadelphia, Pennsylvania, in the year 1876; second, a representation, on the other side of said medal, of the interior of said Centennial Exposition buildings, both substantially as shown.

Fig. 1 in the accompanying fac-simile is a view of the exterior, and Fig. 2 a view of the interior, of said buildings, which designs are

applied, respectively, to the obverse and reverse sides of a medal in any suitable and appropriate manner.

What we claim as our design is—

1. The design for a medal consisting of a view of the exterior of the buildings of the Centennial Exposition of 1876 on one side, as represented in Fig. 1 of the drawing.

2. The design for a medal consisting of a view of the interior of the buildings of the Centennial Exposition of 1876, as described and shown in Fig. 2 of the drawing.

3. The design for a medal consisting of a view of the exterior of the buildings of the Centennial Exposition of 1876 on the obverse side, and on the other or reverse side a view of the interior of said buildings, as shown.

In testimony that we claim the foregoing we have hereunto set our hands this 23d day of April, A. D. 1874.

T. ROLLASON HARTELL.
JOHN LETCHWORTH.
